JAMES GORDON BENTON, OF MAISONNEUVE, QUEBEC, CANADA, ASSIGNEE, BY MESNE ASSIGNMENTS, OF ONE-HALF TO ANNE MURRAY, OF MONTREAL, QUEBEC, CANADA.

ELECTRICAL PLUG.

1,359,567.

Specification of Letters Patent. Patented Nov. 23, 1920.

Application filed July 28, 1917. Serial No. 183,366.

To all whom it may concern:

Be it known that I, JAMES GORDON BENTON, a subject of the King of Great Britain, and resident of the city of Maisonneuve, 5 Province of Quebec, Canada, have invented certain new and useful Improvements in Electrical Plugs, and do hereby declare the following to be a full, clear, and exact description of the same.

10 This invention relates to a plug for use in connection with electrical resistance devices such as sad irons, bread toasters and the like, for the purpose of making or breaking the circuit therethrough, and distinguishes particularly from plugs for varying 15 the effective resistance capacity of such devices.

The plug to which my invention applies is carried at the end of a flexible conductor 20 cord and adapted to be primarily slipped over the terminal posts of the iron or other device to complete the circuit through the latter. In the use of plugs as heretofore constructed, however, an inconvenience and 25 disadvantage has been perceived owing to the fact that to open the circuit such prior plugs have to be either displaced or entirely removed from the terminal posts and, on the other hand, necessitate a modification 30 in the construction of the standard domestic resistance devices in general use and thus prevent effective employment of the plug with the standard devices.

An object of the present invention is to 35 incorporate in a plug adapted to be slipped over the terminal posts of an electrical resistance device, an element whereby the circuit through the resistance can be positively opened and closed without necessitating 40 displacement of the plug or modification in the construction of the resistance device.

Another object is to provide a simply constructed and compactly incorporated circuit controller and plug adapted to be 45 slipped over the terminal posts of an electrical resistance device.

The objects and advantages will be hereinafter more fully described and particularly pointed out in the appended claims.

50 For full comprehension, however, of my invention reference should be had to the accompanying drawings forming a part of this specification, in which similar reference characters indicate the same parts and 55 wherein:

Figure 1 is a perspective view illustrating my improved plug in use, the plug being partly in section;

Fig. 2 is an enlarged longitudinal section on line 2—2 Fig. 3; and 60

Fig. 3 is a transverse section on line 3—3, Fig. 2.

Referring now to the drawings, the body of the plug is formed of two similar halves 2, 2^a, of insulating material fastened together as by screws or other suitable means, and the terminals are open or exposed to the exterior of the plug at one end and these outer ends are adapted to be slipped over posts 4 forming the terminals of a resistance element (not shown) in a device indicated at 5.

The body of the plug is formed with a recess 6 at the rear of the inner ends of the tubes 3 and a hollow metallic standard 7 is 75 supported in the recess, such standard being slotted longitudinally at 8 to accommodate a metallic rocking bar 9 pivotally supported in the slot by a pin 10 extending through the standard. 80

The rocking bar extends to the front and rear of the standard and is permitted a swinging movement longitudinally of the standard, the bar being actuated through the medium of rigid links 11 and 12 respectively attached to the bar at each side of the standard and extending out through apertures 13 in the body 2 and finger pieces 14 being attached to their protruding ends. 85

A coiled spring 15 is located within the 90 hollow standard at a point above bar 9 and presses downwardly upon the bar through the medium of a ball 16 guided within the standard, the upper edge of the bar being depressed at each side of the pivot pin 10 to 95 form recesses or depressions 17 divided by a partition 18 in line with the pin.

When one end of the bar is depressed by pushing one of the links inward, the partition 18 engages the ball and, forcing same 100 upwardly against the resistance of the spring, passes from one side of the pivot pin to the other and causes the spring pressed ball to pass from one recess to the other. In this manner the depression of 105 one end of the bar and consequent movement of the partition toward one side, causes the ball to move into the recess at the opposite side of the partition and restrain return movement of the latter, the influence of the 110

spring being thus shifted from side to side across dead center position and maintaining the bar in its position inclined to one side of the standard until such time as the 5 other link is pushed inwardly and the spring overcome.

A post 20 supported in recess 6 adjacent standard 7 carries a stationary contact 21 with a spring socket 22 below and in the 10 path of an outwardly and downwardly extending finger 23 in electrical connection with and carried by the rear end of bar 9, such finger, with the bar, constituting a movable contact and being brought into 15 engagement with the socket 22 when the rear end of bar 9 is depressed.

The plug is connected to one end of a conductor cord 24 having two conductors, one of which is connected at 25 to a conducting 20 strip *b* and through it to one of the plug terminals 3 and the other conductor connected at 26 to the stationary contact 21 and, through socket 22, finger 23 when engaged with the latter, and arm 9, to the 25 standard 7 between which and the other terminal 3 a wire 27 extends.

The opposite end of the conductor cord is attached in any suitable manner to the house or other circuit and when so attached 30 and the terminals 3 of the plug inserted over the posts of the resistance device, current passes through the plug along the path described in the preceding paragraph. When it is desired to open the circuit, link 11 at 35 the front of the standard is pushed inward and finger 23 raised out of engagement with socket 22, the spring 15 holding the contact end of bar 9 raised and so maintaining the circuit open until link 12 is depressed to 40 again lower the finger into engagement with the stationary contact.

The above described construction enables a plug to be, as usual, entirely removed from the posts of the resistance device when it is 45 desired to place same away and in addition provides a compact device enabling the circuit to be conveniently opened or closed, independently of the removal of the plug and without necessitating modification in the 50 construction of the resistance device, on occasions when a continuous electric current is undesirable such as in ironing to avoid excessive heating of the iron.

What I claim is as follows:—

55 1. A plug for use in connection with electrical resistance devices, comprising a body of oblong rectangular form and substantially half the length of which constitutes a forward portion tapering toward its end and adapted to carry tubular terminals while the other half or rear portion presents a chamber having four walls, a top

and a bottom, the whole being formed of insulating material; a pair of immovable tubular terminals extending throughout the 65 length of the forward portion and adapted to be slipped over the substantially co-extensive terminals of a resistance device; a conducting strip leading from one tubular terminal along the bottom to the rear wall 70 of the chamber; a standard fixedly mounted on the floor of the chamber and electrically connected to the other tubular terminal; a stationary contact strip extending forward from the rear wall of the chamber and terminating in a contact socket; a rocking bar pivotally mounted in said standard and in electrical connection therewith and carrying a contact finger for movement into and out of contact with said contact socket; 80 means for rocking the bar and means for retaining it in either position to which it may be moved, and a pair of current conductors one of which is connected to the said conducting strip and the other connected to 85 the stationary contact strip.

2. A plug, for use in connection with electrical resistance devices, comprising a body of oblong rectangular form and substantially half the length of which constitutes a 90 forward portion tapering toward its end and adapted to carry tubular terminals while the other half or rear portion presents a chamber having four walls, a top and a bottom, the whole being formed of insulating material and two openings being formed in the top thereof; a pair of immovable tubular terminals extending throughout the 95 length of the forward portion and adapted to be slipped over the substantially co-extensive terminals of a resistance device; a conducting strip leading from the tubular terminal to the rear wall of the chamber; a standard fixedly mounted on the floor of the chamber and electrically connected to 100 the other tubular terminal; a stationary contact strip extending forward from the rear wall of the chamber and terminating in a contact socket; a rocking bar pivotally mounted in said standard and in electrical 105 connection therewith and carrying a contact finger for movement into and out of contact with said contact socket; push buttons located in the openings in the top of the plug and connected with the rocking 110 bar for operating same; a spring device for retaining the bar in either position to which it may be moved, and a pair of current conductors one of which is connected to the 115 conducting strip and the other connected to 120 the stationary contact strip.

In testimony whereof, I have signed my name to this specification.

JAMES GORDON BENTON,
